UNITED STATES PATENT OFFICE.

CHARLES HENRY FULLER, OF PORTLAND, OREGON.

BOAT-DAVIT.

1,194,384.

Specification of Letters Patent.

Patented Aug. 8, 1916.

Application filed October 5, 1915. Serial No. 54,278.

To all whom it may concern:

Be it known that I, CHARLES HENRY FULLER, a citizen of the United States, and a resident of the city of Portland, county of 5 Multnomah, State of Oregon, have invented a new and useful Improvement in Boat-Davits, of which the following is a specification.

This invention relates generally to apparatus used on shipboard for raising and lowering life-boats.

One of the main objects of this invention is to provide improved apparatus of this character by means of which a life-boat may 15 be lifted from its chocks and swung clear of the side of the vessel to such position that it may be dropped to the water in a manner not to be interfered with by the list of the vessel.

Another object is to provide boat davits which will be automatic in action, capable 20 of operation by one man, and which may be controlled, in launching a boat, by the occupant of the boat.

In the accompanying drawings: Figure 1 25 is an elevation of the apparatus, showing the life-boat lifted from its chocks and ready to be swung outward from the vessel; Fig. 2 is a right-end elevation of the parts shown 30 in Fig. 1. In this view the davit arms have been swung to horizontal position so as to place the boat clear of the vessel; Fig. 3 is a sectional view taken on line 3-3 of Fig. 1, and showing the novel form of the eccentric 35 brake-disk; and Fig. 4 is a fragmental left-end elevation of the parts shown in Fig. 1.

a represents a vessel on which my boat-davits are used. Mounted on the deck of this vessel are the pedestals *b*, *c*, which 40 form bearings for my device. A longitudinal shaft *d* is journaled in these pedestals and rigidly mounted on the shaft are the davit arms *e*, *e'*. The outer extremities of the latter are provided with box-like housings *f*, *f'*, in which are rotatably mounted the sheaves *g* and the fair-leaders *h*, located in transverse planes relatively to each other. An auxiliary sheave, *i*, is mounted 45 in the housing *f'*.

j represents a life-boat provided at its opposite ends with hook-eyes *j'*. Boat-falls *k*, by which the boat *j* is raised or lowered, are provided with davit-hooks *k'*, adapted to engage the eyes *j'*, and said falls run between 50 the fair-leaders *h* and over the sheaves *g* to the winding drums *l*, *l'*. Between the davit-

arms *e*, *e'* and loosely mounted on the shaft *d* is a sleeve *m*, and the winding drums *l*, *l'* are rigidly mounted on the ends of this sleeve. Each drum is made with an integral brake drum *n*, *n'*. Journaled in bearings *o*, *o'*, beneath the shaft *d*, is a shaft *q*, and fixed on the latter, in vertical alinement with the brake-drums *n*, *n'* are eccentric brake-disks *p*, *p'*. Brake bands *q'*, *q''* connect the drums *n*, *n'* respectively, and the eccentric brake-disks *p*, *p'*. A partial rotation of the shaft *q* will cause said eccentrics to be rotated so as to place the tension in the brake-bands and thus exert a braking 65 action on the sleeve *m*. The brake operating means consist of a foot lever *r* pivoted on a bearing *r'*, and normally rocked counterclockwise by a tension spring *r''*. A lever arm *o''* is fixed on one end of the shaft *q*, 70 and a link *r'''* connects the end of the foot pedal *r* with said lever arm *o''*. A depression of the foot-pedal will rock the shaft *q* so as to release the brakes, said brakes being 75 otherwise held in engagement by the spring *r''*.

Mounted on the deck of the vessel are abutments *e''*, *e'''*, which serve as stops to limit the clockwise rotation of the davit arms. See Fig. 2. A sheave *e''* is mounted 85 on the abutment *e'''* and a brake line *s*, running over said sheaves *e''* and *i* has one end connected to the lever arm *o''*, the other end following loosely in the life-boat *j*. When the occupant of the life-boat exerts a pull on 90 the brake-line *s*, the winding drums *l*, *l'* will be unbraked and the boat will drop by gravity; the speed of the drop being controlled by the brake-line *s*.

On the left end of the shaft *d* is fixed a 95 sheave *t*. A pair of opposed tension coil-springs *t'* are fixed on pivots *t''*. The springs may extend below the deck, or they may be located in any other convenient position. The outer ends of the springs are provided with cables *t''*, which are fixed at the points *t'''* to opposite sides of the sheave *t*. These springs are so balanced that when in equilibrium the davit arms will be positioned off center, as shown in Fig. 4. 100 105

On the right end of the shaft *d* is fixed a gear *u* and parallel to said gear, but loose on the shaft *d*, is a similar gear *v*. A gear *v'* is integrally formed on the brake drum *l'*, and the gears *v*, *v'* are connected through 110 the medium of gears *v''*, *v'''*, these latter being mounted on a shaft *v''* in the pedestal *c*.

The gear u is provided with an integral brake drum u' . A foot lever w , pivoted at w' , is normally rocked counter-clockwise (see Fig. 2) by a tension coil-spring w^2 . A 5 brake-band w^3 , encircling the brake-drum u' , is connected to said foot lever so that normally the tension of the spring w^2 will hold the brake in operative engagement, and thereby hold the shaft d and davit arms e, e' 10 in any position. A depression of the foot-pedal w will release the brake.

The pedestal c is formed at its upper end with a bearing c' in which is rotatably mounted a shaft x , a portion of which is of squared cross-section, as indicated by x' . The crank arm x^2 is adapted to engage the outer end of the shaft x , so as to rotate the latter, and a gear y is slidably mounted on the squared portion x' of said shaft. A gear shift lever z , pivoted at z' , is adapted to engage a shifter collar y' of the gear y , so that the operation of said gear shifter will move the gear y into engagement with either of the gears u or v , or both at the same time; 20 said gear being made with a face of sufficient width to permit of the latter engagement.

The general operation of this type of boat davit is as follows: The life-boats may be 30 mounted in chocks in any position on the deck within range of the davit arms e, e' . The gear y is thrown into engagement with the gear u , the pedal w is then depressed, and the shaft d rotated until the davit arms 35 are in proper position over the life boat, whereupon the pedal w is released so as to hold the shaft d in such position. The davit-hooks k' are then engaged with the eyes j , the boat is loaded, the pedal depressed, and the shaft d will be automatically rotated by 40 the unequal tension in the springs t' to the position shown in Fig. 4. Gravity will then allow the davit arms and boat to drop to the position shown in Fig. 2. The brake on the 45 winding drums l, l' may be then released by the pressure on the foot pedal r , or the brake-line s may be pulled by an occupant of the boat, thereby allowing the boat j to be lowered to the water entirely clear of the 50 side of the vessel, so that any list of the latter will not be dangerous.

When a boat is to be raised from the water the gear shift lever z is moved in the 55 position shown in Fig. 1, so as to engage the gear y with the gear v . The foot lever r is depressed so as to release the brake on the winding drums l, l' , and the crank x^2 is then operated so as to rotate the sleeve m and thereby the drums l, l' . The gear y may 60 be placed in intermediate position so that it will be in position at the same time with both gears u and v , and in this way it is

possible to elevate the boat and the davit arms simultaneously.

I claim:

1. In a life-boat launching apparatus, a 65 rotatable main shaft, davit arms fixed on said shaft, a tubular shaft rotatably mounted on said main shaft, and selective means for rotating said main shaft and tubular shaft independently or in unison.

2. In a life-boat launching apparatus, a 75 rotatable main shaft, davit arms fixed on said shaft, winding drums rotatable on said main shaft, and selective means for rotating said main shaft and winding drums independently or in unison.

3. In a life-boat launching apparatus, a 80 rotatable main shaft, davit arms fixed on said shaft, a tubular shaft rotatably mounted on said main shaft, winding drums fixed on said tubular shaft, and means for holding said main shaft and tubular shaft in any position to which they have been rotated.

4. In a life-boat launching apparatus, a 85 rotatable main shaft, davit arms fixed on said shaft, a tubular shaft rotatably mounted on said main shaft, and means for holding said main shaft and tubular shaft in any position to which they have been rotated.

5. In a life boat launching apparatus, the 90 combination of companion shafts independently rotatable about a common axis, davit arms mounted on one of said shafts, and selective means for rotating said shafts independently or in unison.

6. In a life boat launching apparatus, the 95 combination of companion shafts independently rotatable about a common axis, davit arms fixed on one of said shafts, winding 100 drums fixed on the other of said shafts, selective means for rotating said shafts independently or in unison, said davit arms being provided on their outer ends with boat-falls guiding elements, boat-falls connected to said winding drums and running over said guiding elements, and means for holding either shaft in any position to 105 which it has been rotated.

7. In a life-boat launching apparatus, a 110 rotatable main shaft, davit arms fixed on said shaft, winding drums rotatable independently of said davit arms, selective means for rotating said main shaft and winding drums independently or in unison, 115 said davit arms being provided on their outer ends with fair leaders and sheaves, the latter located transversely to said fair leaders, boat falls connected to said winding drums and running over said sheaves 120 and fair leaders, and means for holding said main shaft and winding drums in any position to which they have been rotated.

CHARLES HENRY FULLER.
